ROBERT HOE, OF HYDE PARK, NEW YORK.

IRONING MACHINE.

Application filed May 29, 1926. Serial No. 112,423.

This invention relates to ironing machines of the type provided with safety release mechanism in case the operator's hand is caught between the padded roll and heated surface, and has for its object to provide a quick detachable connection between the roll and its driving means. Another object is to provide such a safety mechanism in a machine of the type where the rolls are capable of being rotated when either in contact with or spaced from the heated surface.

In machines having safety release mechanism permitting the release of pressure between roll and heated surface in case the operator's hand or arm is caught therebetween, the roll gear or other driving means on the shaft is usually released and moves along with the roll. It has previously been impossible to combine such safety release features in machines in which the roll driving means cannot be released, as for example, when driven by a chain or when in mesh with a driving gear in such position as to be precluded from moving in the direction in which the roll is moved when released.

According to this invention a quick detachable connection is provided between the padded roll and its driving means so that only the roll and not the driving means is moved on release of pressure upon the roll. Specifically, a quick detachable connection is used which permits the roll shaft to be moved out of alinement with its driving shaft while still maintaining the driving relation, so that the advantage of safety release for the roll may be combined with the advantages of a machine in which the roll is positively driven or not when in any of its normal operating positions contacting with or spaced from the heated surface.

Figure 1 is an end view of an ironing machine embodying this invention and corresponds to a view taken on the line 1^a—1^a of Figure 2.

Figure 2 is a front view of Figure 1 showing the driving gear in section.

The ironing machine of this invention comprises a pair of end frames 1 and 2 supporting upper frames 5 and 6. The heated surface, preferably in the form of an ironing cylinder 3 is journaled in these frames as shown in Figure 2, and is rotated from any convenient source of power, not shown, by the gear 4 fixed on shaft 7. The cylin-

der 3 may be heated by means of a gas pipe 8 extending lengthwise through the rotatable shaft 7. A feed table 9 is positioned adjacent the upper part of cylinder 3, being supported by brackets 10, formed integral with frames 5 and 6.

The upper frames 5 and 6 are provided with the usual guideways 11 in which the bearing boxes 12 are slidably mounted. Shafts 13 are journaled in bearing boxes 12 and carry padded rolls 14, 15 and 16. The rolls are driven by roll gears 17 all of which mesh with cylinder gear 18 on shaft 7. It will generally be found advisable to make gears 17 of decreasing size from front to rear so that each roll is given a peripheral speed slightly greater than that of the roll preceding it, in order that the goods passing through the machine may be slightly stretched while being ironed, but this is not necessary. Each of the rolls 14, 15 and 16 is provided with end flanges 19 between which suitable padding may be placed. The padding on each roll comprises a light canvas or other sheet fabric wound around the roll a number of times and preferably depending on rotation of the roll to keep it wound tight.

Across the tops of the forward guideways 11 bridges 20 are positioned. Housings 21 and 22 are preferably formed with caps and contain the coiled springs 23 which co-operate with the bearing boxes 12 to yieldingly press the rolls against the cylinder. For raising said rolls, a cam roller 24 is mounted on each end of each roll to contact with the cams 25 which are pivoted to the end frames by studs 26. The cams 25 are provided with large central openings whereby the supply of air for the gas burner within the cylinder is facilitated. A cross bear 27 extends between levers 28 secured to cams 25 and is connected, by means not shown, to a treadle whereby the cams may be rotated to lift the rolls from the cylinder.

Each roll shaft 13 is provided with a collar 30, keyed thereto, which has a slot 29 extending diametrically across its face. Each roll gear 17 is provided with a similar slot 31 and an Oldham coupling 32 is positioned between and engages these two slots, which are thus held at right angles to each other. The purpose of this arrangement is to make it possible for the rolls to be driven in either raised or lowered position, the change in alinement between shaft 13 and

gear 17 being taken care of by the Oldham coupling which permits the shaft to be displaced from the axis of its driving gear and still have the gear effective to drive the shaft. Another function for the Oldham coupling is that of a quick detachable connection between the roll and its driving gear so that on release of the spring the roll may be moved entirely out of its guideways, the Oldham coupling serving to disconnect the roll from its driving means. A special feature is the quick detachable characteristic combined with its ability to drive the roll when the axes of the driving gear and roll do not coincide.

Gear 17 for each roll is mounted on an eccentric stud 33 whereby it may be raised out of engagement with cylinder gear 18. A crank 34 is keyed to stud 33 and carries a spring pressed pin 35 adapted to engage either of two holes 36 in frame 37. Pin 35 may be raised out of engagement with hole 36 by pulling outwardly on knob 38. It will thus be seen that if crank 34 is rotated through 180 degrees from the position shown in Figure 2, gear 17 will be disengaged from gear 18; thereby leaving the roll free so that it will not rotate unless the cam 25 is in such position that the roll contacts with the cylinder, in which case the cylinder will frictionally drive the roll. Each of bridges 20 is pivoted by means of a stud 39 to the upper frame, and carries a pin 40 at its forward end. Levers 41 and 42 are pivoted at 43 to frames 5 and 6 and carry lugs 44 adapted to engage pins 40 to hold the bridges 20 in operative position to give the desired pressure to the rolls. A safety bar 45 extends between levers 41 and 42.

To operate the safety mechanism, the safety bar 45 is moved in either direction, causing lugs 44 to disengage from pins 40 whereupon the reaction of springs 23 causes bridges 20 to swing upwardly, or the springs may throw the bridges over so as to completely uncover the guideways and allow the rolls to be removed from the machine. In either case, the rolls are held against the cylinder only by their own weight and the hand of the operator may be withdrawn. If it happens that both hands of the operator are simultaneously caught under the roll 14, the releasing mechanism can be actuated by a slight pressure of the shoulder against any portion of the safety bar 45. In order to render the operation of the safety mechanism an instinctive act, the bar is placed in an overhanging position with respect to the feed table 9, so that the operator, in bracing himself to extract his hand, will push the bar either with his free hand or with his shoulder and thereby free himself, no matter how the bar 45 be moved.

The third or rear roll 16 is not held down by bridges, but is held in position by a boss

47 carrying the spring housing 46 and is not released when the safety bar is moved, since it is very unlikely that the operator's hands would be engaged by that roll.

It will thus be seen that the invention provides a safety mechanism which may be operated by being pressed either forwardly or backwardly and that the engagement of both hands by the rolls will not prevent the operator from pressing the bar to release the pressure of the rolls.

Ability of the release actuating bar to function when moved in either direction prevents dangerous delay and precludes a new operator actuating the bar in the wrong direction. The positive drive for the rolls when either up or down prevents scorching of the rolls when separated from the heated surface and enables the material being ironed to be polished, by giving the rolls a slightly different speed from that of the heated surface. The ability of the padded rolls to be freely rotated and not positively driven when either raised or in contact with the heated surface, permits friction drive for a dull finish on the material being ironed, and also enables the padding on the rolls to be changed with greater ease and facility and without the necessity of one roll driving another in unwinding or winding the padding. The quick detachable connection enables the roll to be released without carrying with it its driving gear, and at the same time the particular type of the quick detachable connection used here, namely the Oldham coupling, enables the roll to be driven by its gear when not in alignment.

This invention combines the advantages of manual release for the rolls with the advantages described in connection with the machine of my pending applications Serial No. 648,206, filed June 28, 1923, for ironing machine, and Serial No. 722,434 for ironing machine filed June 26, 1924, of which the present application is a continuation in part, with the result that the machine of this invention possesses more advantages and greater flexibility than any previous ironing machine.

I claim:

1. In an ironing machine the combination with a heated surface, of a padded roll, means to press the roll against said surface, means for separating said roll and surface, means for rotating said roll, means for quickly releasing pressure between said roll and heated surface, and a quick, detachable connection located between said rotating means and said roll.

2. In an ironing machine the combination with a heated surface, of a padded roll, means to press the roll and surface together, means for separating said roll and surface, means for rotating said roll, means for quickly releasing said roll and surface.

pressing means, and a quick detachable connection comprising an Oldham coupling between said rotating means and said roll.

3. In an ironing machine the combination with a heated surface, of a padded roll, means for pressing the roll and surface together, means for separating said roll and surface, means for rotating said roll, means for quickly releasing said roll pressing means, and a quick, detachable driving connection located on the roll shaft between said rotating means and said roll.

4. In an ironing machine the combination with a heated surface, of a padded roll, means to press the roll and surface together, means for separating said roll and surface, means for rotating said roll, a feed table across the front of said machine and at about the level of the contact between said roll and surface, means for quickly releasing said roll pressing means, and actuating means for said releasing means located at the front of said machine, substantially over said feed table, and including a lever having means whereby a movement thereof toward or away from said feed table releases said roll pressing means.

5. In an ironing machine the combination with a heated rotatable cylinder, of a padded roll contacting therewith, a bridge associated with said roll, a spring interposed between said bridge and said roll and adapted to press the roll against the cylinder, a lever having means to hold said bridge against said spring, and means whereby a movement of said lever in either of two directions disengages said bridge.

6. An ironing machine comprising a cylinder, a plurality of rolls adapted to co-

operate therewith, a driving means for said rolls, means for separating said rolls from the cylinder, and for rotating the rolls when in contact with or separated from said cylinder, means for disconnecting any one of said rolls from its driving means, means for resiliently pressing said rolls against said cylinder, and safety means for releasing such pressure.

7. An ironing machine comprising a frame, a heated surface mounted therein, a feed table adjacent said heated surface, a plurality of rolls adapted to co-operate with said heated surface, driving means for said rolls, a pair of bridges pivoted to said frame, springs carried by said bridges and engaging the bearings of the rolls to press the rolls into contact with the heated surface, a pair of levers pivoted to said frame and engaging said bridges, said levers having means whereby a movement thereof toward or from the feed table releases said bridging members, and a safety bar extending between said levers and overhanging said feed table.

8. In an ironing machine the combination with a heated surface, of a padded roll, spring means to press the roll toward said surface, means for rotating said roll when either contacting with or spaced from said surface, and latch means operative without moving the roll for quickly releasing the tension of the springs upon said roll when the same is either raised from or in contact with said surface.

Signed at Hyde Park on Hudson, in the county of Dutchess, and State of New York, this 27th day of May A. D. 1926.

ROBERT HOE.
